In Canada October 14, 1952

Term of patent 14 years

(Cl. D44—9)

To all whom it may concern:

Be it known that I, George Robert Palmeter, a citizen of Canada, residing at Kentville in the Province of Nova Scotia, Canada, have invented a new, original, and ornamental Design for a Saucer or Similar Article, of which the following is a specification, reference being had to the accompanying drawing forming a part hereof.

The figure is a plan view of a saucer, showing my new design.

The configuration of the saucer is of a conventional appearance view from the side or bottom thereof.

I claim:

The ornamental design for a saucer or similar article, as shown and described.

GEORGE ROBERT PALMETER.
